UNITED STATES PATENT OFFICE.

NORMAN C. ELLIS AND HUBERT C. ELLIS, OF EVANSTON, ILLINOIS, ASSIGNEES TO ELLIS DRIER & ELEVATOR COMPANY, OF CHICAGO, ILLINOIS, A CORPORATION OF WISCONSIN.

GRAIN-DRYING APPARATUS.

Application filed March 20, 1922. Serial No. 544,987.

To all whom it may concern:

Be it known that we, NORMAN C. ELLIS and HUBERT C. ELLIS, both subjects of the King of Great Britain, and residents of 5 Evanston, in the county of Cook and State of Illinois, have invented certain new and useful Improvements in Grain-Drying Apparatus, of which the following is a full, clear, and exact description.

10 The invention relates to grain drying apparatus.

In grain dryer installations and more particularly those used with small elevators, a compact apparatus, including the drier, 15 cooler, boiler, heater and blower has been a desideratum and one object of the invention is to provide such a unit which may be conveniently installed and which will be efficient in operation. Another object of the 20 invention is to provide an improved grain drying apparatus in which the heater for drying fluids, such as air, is mounted directly on, and directly connected to, the boiler, so that radiation losses resulting from 25 conducting the steam from the boiler to the air ducts of the drier will be avoided.

The invention consists in the several novel features hereinafter set forth and more particularly defined by claims at the conclusion 30 hereof.

In the drawings: Fig. 1 is a front elevation of apparatus embodying the invention. Fig. 2 is a side elevation. Fig. 3 is a section, parts being shown in elevation. Fig. 4 is 35 a detail of the heater pipes and their connections with the boiler.

The invention is exemplified in a structure comprising a grain drier 11 in which the grain is subjected to a blast of hot air 40 and a cooler 12 into which the grain passes from the drier and in which it is subjected to a blast of cold or unheated air. This drier and cooler may be of any suitable construction, for example, as that set forth in 45 Letters Patent No. 1,127,794, dated Feb. 9, 1915, so that a detail illustration and description thereof are not deemed necessary. The drier illustrated in said patent embodies a series of grain shafts through which 50 the grain descends in continuously settling columns, passing from the drier to the cooler under control of suitable valve-mechanism 55 and into similar shafts in the cooler. The grain passes through the cooler in settling columns and is discharged from the lower

end thereof under control of a suitable valve 16. The structure forming the drier and cooler is supported on a suitable framework 17.

The apparatus comprises a steam boiler 18, a blower 21, an intake 22 for the blower which is connected to the exhaust ducts of the cooler by a trunk 20, so that air will be drawn into the intake ducts of the cooler through the grain in the shafts, the exhaust ducts of the cooler and said trunk to the intake-eye of the blower. A discharge trunk 19 is connected to the outlet of the blower 21 to deliver air from the blower to the air-supply trunk 23 for the drier 11. Heater 24 extends vertically through the trunks 20 and 23, so that air in transit to the blower from the cooler and from the blower to the drier will be heated. The hot air from the trunk 23 will be forced through the intake 75 ducts, grain columns and exhaust ducts in the drier 11 and then discharged.

The casing 21^a of the blower 21 is mounted on, and supported by, the boiler 18 which is preferably of the sectional type. The trunk 20 is supported on the boiler, as at 25, and the portion around the heater 24 is open to the top of the boiler. The heater comprises steam pipes 26 which are secured in the wall 27 which forms the top of the steam chamber and are surrounded by radiator pipes 28 which are secured in, and extend upwardly from, the top wall 29 of the boiler. The upper ends of the pipes 28 are closed and the upper ends of the pipes 26 terminate 90 near the upper ends of the pipes 28, so that the condensate will pass downwardly through pipes 28 into the chambers 30 which conduct the condensate into the water legs of the boiler.

In operation, cold air will be drawn through the grain in the cooler and through the trunk 20 to the inlet of the blower 21 and then forced by the blower through trunks 19 and 23 and through the grain drier unit 11. In transit through trunks 20 and 23, the air will be heated so that the grain in the drier unit will be subjected to a blast of hot air.

A characteristic of the invention is that the blower and intake and exhaust trunks are mounted on the boiler used to supply steam to the heater which makes possible a compact structure in which the boiler is combined with the drying apparatus. An-

other characteristic is that the trunks, through which the air is drawn, are disposed above the boiler so that pipes rising directly from the boiler may be utilized to heat air in transit to the drier unit. The structure, in its entirety, in which boiler, heater, blower and cooling and drying units are combined, is of particular advantage in 10 installments for small elevators where economy of space is a factor.

The invention is not to be understood as restricted to the details set forth, since these may be modified within the scope of the appended claims, without departing 15 from the spirit and scope of the invention.

Having thus described the invention, what we claim as new and desire to secure by Letters Patent, is:

1. The combination of a drier, a boiler, a 20 duct for delivering drying fluid to the drier extending over the boiler, a steam heater for said fluid mounted directly on top of and connected to receive steam from the boiler and extending across said duct, and 25 means for forcing fluid through said duct to the drier.

2. The combination of a drier, a steam 30 boiler, a duct for delivering drying fluid to the drier extending over the boiler, a steam heater for said fluid comprising a series of 35 pipes mounted on and adapted to receive steam directly from the top of and connected to receive steam from the boiler and extending upwardly therefrom into said duct, and means for forcing fluid through said 45 duct to the drier.

3. The combination of a drier, a steam 40 boiler, a duct for delivering drying fluid to the drier, extending over the boiler, a heater for said fluid comprising inner and outer 45 pipes connected directly to top of the boiler and extending upwardly therefrom into said duct, and means for forcing fluid through 50 said duct to the drier.

4. The combination of a drier, a boiler,

a duct for delivering drying fluid to the drier, a heater for said fluid in the duct, and means for forcing fluid to the drier, mounted on the top of the boiler.

5. The combination of a drier, a boiler, a 50 duct for delivering drying fluid to the drier, a heater for said fluid in the duct, and a blower for forcing fluid to the drier comprising a casing mounted on the top of the boiler. 55

6. The combination of a drier, a boiler, a duct for delivering drying fluid to the drier, a heater for said fluid connected to the top of the boiler and extending upwardly across said duct and a blower for forcing fluid 60 around the heater and to the drier, mounted on top of the boiler.

7. The combination of a drier comprising superposed cooler and drier units, a boiler, a blower mounted on the top of the boiler, a 65 duct for delivering fluid from the cooler-unit to the blower, a duct for delivering fluid from the blower to the drier unit and a heater in said ducts.

8. The combination of a drier comprising 70 superposed cooler and drier units, a boiler, a blower, a duct for delivering fluid from the cooler unit to the blower, a duct for delivering fluid from the blower to the drier unit, said ducts extending over the boiler, 75 and a series of heater pipes connected directly to the top of the boiler and extending upwardly across said ducts.

9. The combination of a drier comprising superposed cooler and drier units, a boiler, 80 a blower mounted on the top of the boiler, a duct for delivering fluid from the cooler unit to the blower, a duct for delivering fluid from the blower to the drier unit, and ducts being extended over the boiler, and a 85 series of heater pipes connected directly to the top of the boiler and extending upwardly across said ducts.
